COMBINED WATCHCASE AND BAND
THEREFORRobert A. Barré, New York, N. Y., assignor to
Schlumberger, Inc., New York, N. Y., a corpora-
tion of New York

Application July 16, 1947, Serial No. 761,282

5 Claims.

(Cl. 224—4)

1

The present invention relates to a combined wrist watch case and band therefor.

It is an object of the present invention to provide a combined wrist watch case and band therefor in which the watch case constitutes an integral part of the band.

It is another object of the present invention to provide a combined wrist watch case and band in which the watch case is an element in the mechanism for closing and locking the band about the wrist of the wearer.

It is also an object of the present invention to provide a combined wrist watch case and band in which the wrist pressure is a factor in keeping and maintaining the case and band safely and securely locked about the wrist.

It is still another object of the present invention to provide a wrist watch case and band combination in which the interlocking means for the case and band about the wrist are located in a readily and easily accessible position for increased convenience in manipulation.

It is yet another object of the present invention to provide a combined wrist watch case and band of the character described which may be easily and readily interlocked and opened by a simple single operation.

It is a further object of the present invention to provide a combined wrist watch case and a band of the character described having locking means of highly simplified construction and design, in which all intermediate and extraneous locking devices, such as latching or hooking mechanisms, now conventionally used, are completely eliminated.

It is a still further object of the present invention to provide a combined wristwatch case and band of the character described which is capable of a great variety of novel and decorative treatment in its exterior design as well as in the arrangement and construction of its parts and elements.

The foregoing and other advantages and superiorities of the combined wrist watch case and band of the present invention will become more readily apparent to those skilled in the art from the embodiment thereof shown in the accompanying drawings and from the description following. It is to be understood, however, that such embodiment is shown by way of illustration only, to make the principles and practice of the invention more readily comprehensible, and without any intent of limiting the invention to the specific details therein shown.

In the drawings:

2

Fig. 1 is a foreshortened, plan view of one embodiment of a combined wrist watch case and band therefor of the present invention;

Fig. 2 is a side elevation of the same, showing the case and band in unlocked relation;

Fig. 3 is a view similar to that of Fig. 2, showing the case and band interlocked; the broken line figure indicating a step in the locking operation; and

10 Fig. 4 is an end view of the case, as seen from the left of Fig. 1, showing one of the locking elements of the case.

Referring more specifically to the accompanying drawings, the combination of watch case and band of the present invention may comprise a case, generally designated as 10, and a band adapted to retain the case about the wrist of the wearer and generally designated as 11. The case 10 may, in general, be of any desired size, shape, style and outline and may be formed of any material conventionally used for the purpose. The band 11 may also be of any desired material, style and construction conventionally in use.

25 The case 10 may have, in its overall construction, the bottom wall 12, the top 13, the side walls 14 and end walls 15 and 16, respectively.

In the preferred embodiment shown, the side walls 14 extend, in one direction, as in the direction of end wall 15, beyond such wall, to form the lugs 17 through which may pass and be removably held the pin 18, which engages one end of the band 11. The top wall 13 may, if desired for the purpose of improved appearance, extend over the lugs 17, to present a continuous top surface.

The top 13 of the case 10 may slope downwardly in the direction of the end 16, as at 20, and part of the slope may overhang the bottom 12 of the case, the overhanging portion being, preferably offset from the bottom 12 to form a recess 21, within which may extend, in protected position, a winding stem 22 of a watch movement arranged within the case.

45 It may here be stated that for the purposes of the present invention it is not material where the receptacle portion and where the cover portion of the watch case begin and end; the overall exterior of the watch case being the only concern of the invention; although the illustrative embodiment of the invention shows the bottom wall as being the sole exposed portion of the watch movement receiving portion of the case.

A frame 25, adapted to fit about the periphery 55 of the case 10, is carried on the free end of the

band 11, and may be secured thereto in any desirable, suitable manner, as by means of the pin 26, passing through the end of band 11 and through the spaced ears 21, secured to one of the sides of the frame 25.

The frame 25 may be fitted around the periphery of the case 10, to enclose all or part of it, and may be separably engaged thereon, as by friction, snap on means, or the like, so that the watch case may be arranged on the wrist and the band passed around it and the frame fitted over the case and engaged thereon. In the illustrative embodiment of the drawings, the forward faces of the lugs 17 are provided with longitudinally disposed grooves 29, which are adapted to receive and hold the forward side 30, of the frame 25. The rear wall 16, which may preferably slope, may be provided, adjacent its upper edge, with a projecting lip 31, preferably extruded therefrom, over which the rear side 32, of the frame 25, may snap into place after the forward side 30, thereof, is engaged in the grooves 29, thereby completely engaging the free end of the band 11, on the case 10. A second extruded lip or projection 33, may be formed at the bottom of the rear wall 16 of the case 10 to prevent downward displacement of the frame relative to the case.

It will be readily apparent that the band locking means of the combined wrist watch case and band of the present invention is conveniently located for manipulation at the back of the wrist, rather than at the front thereof as prevails with band locking devices now conventionally used; that it is easy to manipulate for opening and closing; that it forms a safe and secure closure by reason of the wrist pressure which tends to maintain the case and frame in interlocked relation once they are interengaged.

It will also be readily apparent that many modifications and variations of the combination of the present invention may readily suggest themselves and be made by any one skilled in the art, in accordance with the principles of the invention hereinabove set forth and without the use of any inventive ingenuity. I desire, therefore, to be protected for any and all such variations and modifications that may be made within the spirit of the present invention and within the scope of the claims hereto appended.

What I claim is:

1. A combined watch case and band therefor,

comprising a watch case, a band secured by one end to one side of said case, a frame on the other end of said band adapted to fit about said case, a groove on one side of said case adapted to receive one side of said frame and a projection on an opposed side of said case adapted to retain an opposed side of said frame, whereby said frame may be releasably interengaged on said case.

- 5 2. A combined watch case and band therefor, comprising a watch case having substantially upright wall portions, a band secured by one end to one side of said case, a frame on the other end of said band adapted to fit about the upright portion of said case, a groove on one of said upright wall portions adapted to receive one side of said frame and a projection on the opposed upright wall portion adapted to retain the opposed wall of said frame.
- 10 3. The combined watch case and band therefor of claim 2, wherein the said groove is formed on the side of the case opposite the side by which it is secured to the said band.
- 15 4. The combined watch case and band therefor, comprising a watch case having substantially upright wall portions, a band secured by one end to one side of said case, a frame on the other end of said band adapted to fit about the upright wall portions of said case, an inward de-
- 20 30 pression on one of said upright wall portions adapted to receive therein a portion of said frame, and means on an opposed upright wall portion for receiving an opposed portion of said frame.
- 25 35 5. The combined watch case and band therefor of claim 4 wherein the said opposed frame portion is adjacent to its point of connection to said band.

ROBERT A. BARRÉ.
